UNITED STATES PATENT OFFICE

WILLIAM ROY PENCE, OF MEMPHIS, TENNESSEE

DOORCHECK

Application filed July 2, 1928, Serial No. 289,750. Renewed December 20, 1930.

This invention relates to door checks and aims to provide a novel form of check embodying a magnet including poles designed to contact with an iron plate carried by the door to hold the door in its open position, by the magnetic force of the device.

An important object of the invention is to provide means for retarding movement of the door as the door is swung into engagement with the device, thereby preventing slamming of the door against the stop and the resultant damage to the door.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a view illustrating the application of the door check.

Figure 2 is a plan view of the door check.

Figure 3 is a sectional view taken on line 3—3 of Figure 2.

Referring to the drawing in detail, the device includes a base 5 formed with openings to receive securing screws whereby the device may be secured to the floor surface at the point where it is desired to have the door stand open.

Mounted on the base 5, is a rectangular magnet 6 having poles 7 and 8 respectively, which are connected by means of the bar 9 formed of brass or other non-attractive metal. This bar 9 is formed with an opening defining a guide for the rod 10 which has a head 11 at its outer end.

The rod is threaded at 12 and accommodates lock nuts 13 that are positioned on opposite sides of the iron bars 14, the bar having openings to accommodate the guide pins 15 which are formed of brass and secured to the magnet. An opening 16 is formed in the rear bar of the magnet and defines a guide for the inner extremity of the rod 10, so that

the rod will move in a true horizontal plane without danger of binding.

Associated with the magnet is an iron plate 17 which is carried by the door or closure with which the check is used, the plate 17 being secured to the door by means of the screws 18, there being provided a layer of rubber 19 for insulating the plate 17 from the door.

In the operation of the device when the closure or door carrying the plate 17 is moved rearwardly to contact with the head 11, the rod 10 is moved rearwardly, moving the bar 14 out of engagement with the magnet, retarding the movement of the door to prevent it from slamming against the check when swung to its open position.

It is obvious that should the door be pulled away from the magnet, the magnetic forces will attract the bar 14 returning it to its normal position.

A cover indicated at 20 is positioned over the base and houses the magnet.

I claim:

A door check comprising a magnet having spaced poles, pins extending inwardly from the magnet, a rod spaced between the poles, a plate secured to the rod and having openings to receive the pins, said plate being normally held into engagement with the magnet at the base of the poles, by the magnetic forces of the magnet, a plate secured to the door and adapted to be attracted by the magnet, and said rod adapted to engage the plate secured to the door to move the rod rearwardly and break the contact between the first mentioned plate and magnet.

In testimony that I claim the foregoing as my own, I have hereto affixed my signature.

WILLIAM ROY PENCE.
